[57] ABSTRACT

A clasp for a bracelet which has two legs pivoted relatively to one another at one of their respective ends and the other respective ends of which are adapted to receive a bracelet member. One of the two legs is telescopic and is formed by portions adapted to slide relatively to one another. Two discrete locking assemblies are provided, one for locking the portions of the telescopic leg in each of its respective telescoped positions and the other for locking the two legs of the clasp together and in each of the telescoped positions.

SHEET 2 OF 2

CLASP FOR A BRACELET

The present invention relates to a clasp for a bracket notably one of the open-out buckle type and comprising a form of compass whose flat, curved legs can be locked to one another so that they can substantially follow the shape of the wrist.

It is known that bracelets, and more particularly watch straps, with an open-out buckle-type clasp have great aesthetic advantages but are difficult to adapt to the size of the wearer's wrist.

The problem of the present invention is to eliminate this shortcoming. The invention relates to a clasp of the open-out buckle type which permits the regulation of the length of the buckle formed by the bracelet which it closes.

The present invention therefore has for its object a clasp for a bracelet, notably a watch strap comprising two legs articulated relative to one another at one of their ends and each provided at their other end with means for receiving a bracelet member, notably of leather, having a first means for locking the two legs of the clasp relative to one another, said clasp being characterised in that one of the two legs is telescopic and formed by two portions able to slide relative to one another and that said clasp has a second locking means different from said first means for ensuring the relative positioning of the two portions of the telescopic leg, said first means ensuring the locking of the two legs of the clasp for each of the lengths of the telescopic leg determined by the second locking means.

Advantageously the two legs are flat and curved so that they can substantially follow the shape of the wrist.

Preferably, for making regulation easier, the telescopic leg is in contact with the wearer's wrist.

According to an embodiment of the invention one of the two portions of the telescopic leg is slidably mounted relative to the other via a dovetail slot, the variation of the length of the telescopic leg being determined by a lug carried by one of the portions of said leg and inserted in an oblong hole in the other. Advantageously the locking means according to the relative marked positions of one of the portions of the telescopic leg relative to the other comprises an elastic foil fixed to one of said portions and spaced openings in the sliding direction and a projection which can be inserted in said holes and fixed to the other portion of the telescopic leg.

According to another embodiment one of the portions of the telescopic leg forms a sleeve for the other. In this case the locking means according to the relative marked positions of one of the portions of the telescopic leg relative to the other comprises an elastic portion of the part introduced into the sleeve for at least one projection and a plurality of openings in said sleeve, whereby said projections can be inserted into each of said openings.

Preferably the end of the portion inserted in the sleeve is shaped like a fork with three flat prongs, whereof the central rigid prong opposes the two outer elastic prongs carrying the lateral projections.

As a variant the means for locking the legs on one another can comprise a spring clip fixed to one of the legs and spaced openings in the other leg and whose spacing corresponds to that of the openings in the locking means of the two portions of the telescopic leg relative to one another. In this case advantageously the spring

clip is fixed to the telescopic leg, whereby the spaced openings are provided in the other leg.

According to another embodiment of the invention both legs of the clasp can be telescopic.

The attached drawings give a better understanding of the invention.

FIG. 1 shows in perspective in the open position a clasp according to the invention;

FIG. 2 is a longitudinal section in the closed position of the clasp of FIG. 1;

FIG. 3 is a cross-section along the line III—III of FIG. 2;

FIG. 4 shows one of the portions of the telescopic leg of the clasp of FIG. 1;

FIG. 5 shows in perspective in the open position a variant of the clasp of the invention;

FIG. 6 is a longitudinal section in the closed position of the clasp of FIG. 5;

FIG. 7 is a cross-section along the line VII—VII of FIG. 5;

FIGS. 8 and 9 are respectively cross-sections along the lines VIII—VIII and IX—IX of FIG. 6;

FIG. 10 shows one of the portions of the telescopic leg of the clasp of FIG. 5.

25 The clasp shown in FIG. 1 has two curved, flat legs 1 and 2 each pivoted at 3 at one end so that they are either spaced from one another (FIG. 1) or superposed (FIG. 2).

To the free ends 4 and 5 of legs 1 and 2 are fixed the 30 ends of a bracelet 6, e.g., a watch strap. A platelet 7 having raised edges and fixed to leg 1 masks from the outside the connection of the ends of the bracelet.

Leg 1 is a single member and has at its end 4 a central spring clasp 8.

35 Leg 2 which is in contact with the wearer's wrist comprises two portions 9 and 10 which can slide relatively to one another via a dovetail assembly (see FIG. 3), portion 10 having a slot in which is arranged portion 9. Portion 9 is pivoted at one of its ends at 3 to leg 1. The surface of portion 9 has a projection 11 and a lug 12. Lug 12 is normally introduced in an oblong slot 13 of portion 10 which permits the limitation in both directions of the amount of slide of one portion relative to the other.

45 Portion 10 has an adjustable section 14 provided with spaced openings 15, each of which is able to co-operate with projection 11 of portion 9 to form a locking device for portions 9 and 10 according to the marked relative positions. Finally portion 10 has spaced openings 16 whose spacing corresponds to that of the openings 15 and which are able to co-operate with the spring clip 8 for locking portions 9 and 10 on one another. Thus, whatever the length of leg 2 determined by the choice of a relative locked position of portion 9 relative to portion 10, said two legs 1 and 2 can be locked on one another.

50 Thus the clasp of FIGS. 1 to 4 permits, through the regulation of the length of branch 2, the adjustment of the length of bracelet 6.

55 The embodiment of the clasp according to the invention shown in FIG. 5 has two flat, curved legs 17 and 18, pivoted at 19 at one end so that they can be spaced relative to one another (FIG. 5) or superposed (FIG. 6).

60 To the free ends 20, 21 of legs 17, 18 are fixed the ends of a bracelet 22, e.g., a watch strap. As in the previous embodiment a platelet 23 with raised edges and

fixed to leg 17 permits the masking from the outside of the connection of the two ends of the bracelet 22. Leg 17 is a single member and has a plurality of spaced openings 24.

Leg 18 comprises two portions 25, 26 able to slide relative to one another, whereby portion 26 is a flat sleeve of rectangular cross-section wherein is introduced portion 25 (see FIGS. 7, 8 and 9). Portion 23 is pivoted at one of its ends at 19 to leg 17. Portion 25 has an oblong slot 27 while its end opposite to leg 17 is shaped like a fork with three prongs 28 whereof the central rigid prong opposes the two other elastic prongs, which carry the lateral projections 29. Oblong slot 27 is normally transversed by a lug 30 fixed to portion 26 which permits the limitation, in both directions of the amount of slide of one of the portions relative to the other.

Portion 26 has lateral spaced openings 31 each able to co-operate with a projection 29 of portion 25 to form a locking device for portions 25, 26 according to the marked relative positions. Finally position 26 has a spring clip 32 able to co-operate with each of the openings 24 to lock legs 17, 18 to one another. The spacing of openings 24 correspond to that of the openings 31. In this embodiment the regulation of the length of leg 18 permits the adjustment of the length of bracelet 22.

I claim:

1. Clasp for a bracelet comprising two legs, each having one end pivotally connected to one end of the other

leg and each provided at its other end with means for receiving a bracelet member, first locking means for locking the two legs of the clasp to each other, one of the two legs being telescopic and comprising two portions adapted to slide relative to each other, and second locking means distinct from said first locking means for locking the two portions of the telescopic leg in any of several relative positions corresponding to different lengths of the telescopic leg and defined by spaced openings in one of said relatively slidable portions, said first locking means comprising a spring clip fixed to one of the legs and spaced openings in the other leg spaced by the same distance as the openings in said one slideable portion, said first locking means being adapted to lock the legs of the clasp together with the two portions of said telescopic leg in any of said several positions.

2. Clasp as claimed in claim 1 wherein said spring clip is fixed to the telescopic leg, and the spaced openings are formed in the other leg.

3. Clasp as claimed in claim 1 wherein one of said portions of the telescopic leg is mounted to slide relative to the other by means of a dovetail slot.

4. Clasp as claimed in claim 1 wherein the means for locking one of the portions of the telescopic leg relative to the other comprises an elastic strip fixed to one of said portions and provided with longitudinally spaced holes and a projection on the other portion of the telescopic leg positioned to be inserted in said holes.
